[57] CLAIM

The ornamental design of a remote control for a ceiling fan, as shown and described.

DESCRIPTION

FIG. 1 is a front elevational view of a remote control for a ceiling fan showing my new design;

FIG. 2 is a side elevational view thereof, the opposite side view being a mirror image;

FIG. 3 is a top plan view thereof;

FIG. 4 is a bottom plan view thereof;

FIG. 5 is a front elevational view of the remote control of FIG. 1, shown in an alternative condition of use;

FIG. 6 is a side elevational view showing the alternative condition of use, the opposite side view being a mirror image; and,

FIG. 7 is a rear elevational view of the device as shown in FIG. 1.
